UNITED STATES PATENT OFFICE

139,083

DESIGN FOR A DRAFTING INSTRUMENT

Morris Macht, Baltimore, Md.

Application July 27, 1944, Serial No. 114,579

Term of patent 14 years

(Cl. D52—1)

To all whom it may concern:

Be it known that I, Morris Macht, a citizen of the United States, residing at Baltimore, in the State of Maryland, have invented a new, original, and ornamental Design for a Drafting Instrument, of which the following is a specification, reference being had to the accompanying drawing, forming part thereof.

I claim:

The ornamental design for a drafting instrument, as shown.

MORRIS MACHT.
